UNITED STATES PATENT OFFICE

2,529,202

ANTENNA INPUT CIRCUIT FOR RADIO RECEIVERS

Leo Singleton Tisdale, Sr., Meridian, Miss.

Application June 29, 1945, Serial No. 602,253

1 Claim. (Cl. 250—20)

1

This invention appertains to improvements in radio receiving circuits generally, and has among its several objects and advantages to so modify certain A.-C. and D.-C. radio circuits, particularly those which are battery operated, that received signals will be tremendously amplified and reproduced in a correspondingly increased volume, without distortion and with an appreciable economy in current consumption and, consequently, with a like saving in operating expense.

Another object of the invention has to do with the provision of methods and means for effecting increase in signal strength at both the input and output sides of radio receiving circuits for operation on broadcast wave lengths, as well as those designed for operation on short and television wave lengths, such increase in signal strength and output volume being accompanied with a substantial noise elimination.

Generally, the invention, in its simplest form, consists in imposing plate current from the output tube of a radio receiver on the grid of the R. F. amplifying tube, after the latter has been grounded through the loud-speaker voice coil, or through a coil in series with, or in inductive relation to, the loud-speaker voice coil, i. e., an anti-hum or hum bucking coil. With this circuit arrangement, the output signal strength has been found to increase to an extent that the loud-speaker ordinarily furnished with a receiver will operate at its normal volume with a greatly reduced current consumption, or a much more powerful loud-speaker can be substituted for signal reproduction with an equal, or slightly less, normal current consumption, without signal distortion. In a battery receiver, by actual test, B current for normal operation was found to be reducible by substantially one-half and A current by one-third, with the receiver equipped with the improved circuit arrangements disclosed herein, this saving in current consumption, and consequently in expense of operation, being accompanied with an increase in signal volume, necessitating a reduction in the current supply, or the employment of a more powerful loud-speaker.

With the foregoing and other objects and advantages in view, the invention resides in the certain new and useful combination of circuits and instrumentalities, as will be hereinafter more fully described, set forth in the appended claim, and illustrated in the accompanying drawing, in which:

The figure is a diagram of a nine tube, battery operated, receiver circuit, incorporating the mod-

2

ifying circuits, in accordance with the invention.

In carrying out the objects and purposes of the invention, the first effect of signal volume increase is obtained by grounding the coil of a tuned input circuit through the voice coil of the loud-speaker, or through an anti-hum, i. e., hum bucking, coil that is in inductive relation, or in series, with the voice coil. With these added circuit connections, any positive current, such as the plate current, may then be connected to the bottom of the coil through an electrolytic or other suitable condenser, or even a proper resistor. Also, the positive current so employed may thereafter be connected to the C current anywhere in the circuit, especially, however, to the tubes before the R. F. current goes to the detector tube. While it is appreciated that these circuit changes impose a positive charge on the grid of the I. F. tube, immediately following the transformer secondary, in addition to the negative charge that is normally impressed thereon, the operation of the circuit has proven to be successful in meeting the demand of the invention in actual practice. The second effect of obtaining a marked signal volume increase, i. e., amplification, is to be accomplished by giving the usual aerial-ground system a loop antenna effect, to which end, with an aerial wire of from forty to two hundred and fifty feet length, its input end, beyond its connection with the primary of the inductive couple, will be tapped into the secondary of the latter at its center; it being understood that the secondary may be grounded at any one of several points, for instance, to the antenna primary direct, or otherwise.

Referring to the drawing the invention is incorporated in a receiving circuit of a design found in commercial receivers, such as illustrated by, but not necessarily limited to, that of a Fall 1933 Series—Sears, Roebuck and Company Receiver, and the first of the modifying circuits, as it is exemplified therein, has for its main purpose to charge the grid of a tube, that immediately follows the inductance coil 12 of a tuned input circuit, and this is accomplished by extending a lead 13 between one end of the anti-hum coil 14 and the bottom of the coil 12, and a second lead 15 between the other end of the anti-hum coil 14 and the ground 16. The condenser 17, that is connected between the bottom of the coil 12 and the ground 16, has a value of .1 mfd. and it may be retained in the circuit, or omitted therefrom, depending upon which procedure affords the better results. If left in the circuit,

the lead 15 will be connected between the condenser 17 and the ground 16, as shown.

The second method and means for increasing the output of this standard receiver circuit, with the usual aerial-ground system employed in connection therewith, the aerial 21 being connected to the ground 23 through the primary coil 22, of the inductive couple, a lead 24 is extended between the aerial, immediately adjacent its point of connection with the primary coil 22, and is tapped in at the center of the secondary coil 25 which is in connection with the first of the 951 tubes at the grid thereof. By means of this aerial tap from the secondary coil 25, a loop antenna effect is obtained and results in an appreciable increase in receiver signal volume.

In practice, receivers embodying these modifying circuits have been found to be extremely efficient in operation, not only on broadcast wave lengths, but also on short and television wave lengths, the powerful increases in signal input and output strength and volume being particularly advantageous for betterment in tonal reproduction; in the elimination of interference; and for the increasing the range of signal reception. Greatly increased efficiency in operation will also be realized by employing these modifying circuits in connection with frequency modulation and television circuits, as well as with submarine listening devices in time of war.

Having thus fully described my invention, it is to be understood that variations of and changes in the disclosed receiver modifying circuits, which

will, in like manner, accomplish the objects and purposes set forth herein, may be resorted to, without departing from the spirit of the invention, or its scope as claimed.

5 What I claim is:

In a radio receiving circuit, the combination with an antenna, of a primary inductance having one of its ends connected to said antenna and its other end grounded, a secondary inductance arranged adjacent to and electromagnetically related with said primary inductance and forming part of a tank circuit for controlling the grid of a radio tube, an elongated electrical conductor having one end connected to the antenna side of said primary inductance and its other end connected to the electrical mid-point of said secondary inductance, the connection of said conductor to said inductances providing a loop antenna effect to augment the signal received by 15 said antenna and fed to the grid of the radio tube.
